CAPSULE FILLING APPARATUS

Jacob Leon Lascoff, New York, N. Y.

Application May 11, 1936, Serial No. 78,956

5 Claims. (Cl. 226—40)

This invention relates to apparatus for filling capsules with powder and the like.

A primary object of the invention is to provide an apparatus that will permit the simultaneous filling of a number of capsules with powder and the like.

Another object is to provide such an apparatus that will readily hold a number of capsules in position for filling.

10 A further object is to provide such an apparatus that will hold the filled capsules in position for capping the same.

A still further object is to provide such an apparatus that is simple and rugged in construction and economical in manufacture.

The invention will be better understood from the description thereof to follow taken in connection with the accompanying drawing in which—

20 Figure 1 is a side view partly in section of the improved apparatus.

Figure 2 is a top plan view thereof.

Figure 3 is a section on line 3—3 of Fig. 2.

25 Figure 4 is a fragmentary detail view of a filled capsule with its cap on.

The improved apparatus comprises a rectangular shaped metal base 10 provided with a pair of upstanding posts 11 at each end adjacent its sides. The edges of the upper longitudinal edges 30 of the base are cut away as indicated at 12. At each end of the base between the posts 11 a screw threaded opening 13 is provided; the opening at one end having right hand screw threads and the opening at the other end having left hand screw threads. Mounted for upward and downward movements in each opening 13 is a screw 35 threaded bolt 14. The bolts are threaded to conform to the threads in the openings. Each bolt has fastened thereto a knurled annular member 15 of sufficient diameter to permit a portion of its periphery to extend outside of the end of the base. A pin or lug 16 is formed on the upper surface of the annular member 15. The upper surface of the base is cut out around 40 the openings 13 as indicated at 17 to receive the annular members 15 when at their lowermost position.

A capsule positioning plate 18 is removably mounted on the base. This plate is substantially 45 the same size as the base and is provided with a plurality of holes 19 of any desired size or number. In the drawing, holes of two different sizes are illustrated. At each end of the plate and centrally thereof is a hole 20 and on each side 50 of said hole 20 is a slot 21. A groove 22 is pro-

vided adjacent each longitudinal upper edge of the plate.

A slidable member or bar 23 is mounted on the plate. This bar has guiding and retaining feet or flanges 24 which are adapted to engage the 5 lower surface of the plate. A set screw 25 holds the bar 23 in adjusted position.

In using the apparatus, the plate 18 is mounted in position on the base so that the end openings 20 receive the lugs 16. When in this position 10 the posts 11 extend upwardly through the slots 21. The plate is thus mounted on the upper surface of the annular members 15.

When the number of capsules 26 desired to be filled is ascertained, the slidable bar 23 is 15 slid along over the plate 18 until such a number of holes are exposed on one side of the bar. For example, if it is desired to fill 35 capsules, the bar 23 would be slid to the position shown in

Fig. 2 thereby leaving 35 holes exposed on the 20 left side of the bar. A capsule 26 is placed in each opening 19. The plate 18 is then elevated so that its upper surface is level with the upper edge of the capsules, such as is illustrated in

Fig. 3. This elevating is done by the fingers of 25 the operator turning the annular members 15 so that the bolts 14 will rise in the openings 13 carrying the annular members and the positioning plate with them. A predetermined amount in

30 weight of powder is poured on to the plate and into the openings 19 and any excess powder on the plate can be brushed by a spatula or other tool into the openings. The grooves 22 at the sides receive the excess powder and prevent its

falling over the sides of the plate. The bar 23 prevents any powder from being distributed on the other side thereof. A tamping tool may be used to tamp in the powder in the capsule. If 35 desired the bar 23 may be slid over the openings 19 to level off the powder in said openings. When

the capsules are thus filled, the plate 18 is lowered by turning the members 15 so that a portion 40 of the upper end of the capsule is exposed above the upper surface of the plate 18 as is shown in Fig. 4. When the upper end of the

capsule is thus exposed, its cap or complementary section 27 can readily be placed thereon. The plate 18 with the filled and capped capsules 45 may be removed from the base and the capsules ejected from the holes in any desired manner.

The end grooves 12 permit the flanges or feet 50 24 of the sliding bar to move downwardly, and slots 28 formed on the edge of the plate 18 permit the removal of the bar from the plate without taking the plate off the base.

I claim:

1. A capsule filling apparatus comprising a base, a screw threaded bolt at each end of the base adapted for up and down movements, an annular member having a flat upper surface fastened to the upper end of each bolt, a pin on the upper surface of said annular members, a plate having a plurality of capsule receiving holes and end holes, said plate being removably mounted on the annular members with its end holes receiving the pins, each of said annular members having a portion of its periphery extending beyond the ends of the base for convenience in turning the same and a sliding bar on the plate for indexing the capsule holes and levelling off the powder in the capsules.

2. A capsule filling apparatus comprising a base, a screw threaded bolt at each end of the base adapted for up and down movements, an annular member having a flat upper surface fastened to the upper end of each bolt, a pin on the upper surface of said annular members, a pair of spaced guide posts on each end of the base, a plate having a plurality of capsule receiving holes, end positioning holes and guiding slots, said plate being movably and removably mounted on the annular members with its end holes receiving the pins and its slots receiving the posts, each of said annular members having a portion of its periphery extending beyond the ends of the base for convenience in turning the same, a sliding bar on the plate for indexing the capsule holes and levelling off the powder and a set screw for holding said sliding bar in adjusted position.

3. A capsule filling apparatus comprising a base, a screw threaded bolt at each end of the base adapted for up and down movements, an annular member having a flat upper surface fas-

tened to the upper end of each bolt, a pin on the upper surface of each of said annular members, guide posts on the base, a plate having a plurality of capsule receiving holes, end positioning holes, guiding slots and longitudinal grooves, said plate being movably and removably mounted on the annular members with its end holes receiving the pins and its slots receiving the posts, each of said annular members having a portion of its periphery extending beyond the ends of the base for convenience in turning the same, a sliding bar on the plate for indexing the capsule holes and levelling off the powder, flanges formed on said bar for engagement with the plate for guiding its movement and a set screw carried by said bar for holding it in adjusted position, said plate having slots for permitting the removal of the bar from the plate.

4. A capsule filling apparatus comprising a base, a screw threaded bolt at each end of said base, movable up and down said bolts being threaded in opposite direction, an annular disk having an axial projection on its top face fastened to each bolt for rotating the same, a perforated capsule holding plate resting on said annular disks engaging said projections and a groove along each longitudinal side in said plate to retain powder on said plate.

5. A capsule filling apparatus comprising a base having a threaded bolt at each end movable up and down, an annular disk fastened to each bolt for rotating the same and a central projection above its top, a plate having a pair of registering apertures engaging said projections, and a plurality of capsule receiving holes and a plurality of upright guides on said base engaging said plate to prevent its tilting.

JACOB LEON LASCOFF.
